UNITED STATES PATENT OFFICE.

JOHN GIBBONS, OF WEST TROY, NEW YORK, ASSIGNOR TO THE MENEELY HARDWARE COMPANY, OF SAME PLACE.

HARNESS-SNAP.

SPECIFICATION forming part of Letters Patent No. 322,438, dated July 21, 1885.

Application filed September 12, 1884. (No model.)

To all whom it may concern:

Be it known that I, JOHN GIBBONS, of the village of West Troy, county of Albany, State of New York, have invented a new and useful 5 Improvement in Harness-Snaps, of which the following is a specification.

My invention relates to harness-snaps; and the object of my invention is to simplify and improve their construction.

Accompanying this specification, to form a part of it, there is a plate of drawings containing six figures, illustrating my invention, with the same designation of its parts by letter-reference used in all of them.

15 Of these illustrations, Figure 1 shows a view of the under side of the snap with the bolt-latch removed. Fig. 2 shows a representation of the latch-bolt removed from the snap-body. Fig. 3 illustrates an upper view of the snap-body with the latch-bolt removed. Fig. 4 20 illustrates another view of the latch-bolt, with what is its under side when in position as turned upward. Fig. 5 is a perspective of the completed snap, and Fig. 6 is a longitudinal 25 vertical section taken centrally through the snap and bolt-latch.

The several parts of the snap, and those constituting my invention, are designated by letter-reference, and the function of the parts 30 is described as follows: The letter B indicates the body or barrel of the snap, and the letter G designates a longitudinal groove made in the body of its upper face for the working on its hinge of the latch-bolt. The letters b b 35 indicate bearings made in the under side of the body, near its eye end, for the reception of hinging-journals on the latch-bolt, the body where opposite these bearings being cut out on a line with the groove G, as indicated at 40 O, to receive the rounded end of the latch-bolt. The letters c' and c" indicate cross-partitions made in the groove G, and R a recess between said partitions to receive the snap-spring.

45 The letter L designates the latch-bolt, made with a downwardly-projected and rounded end, E, upon the sides of which are oppositely placed the hinging-journals h h.

The letter N indicates a recess made in the

under side of the latch-bolt, which recess has 50 upwardly-projected from it a pin, p, made to keep in place a spiral spring, S, arranged around said pin.

The letter d designates a clearing-opening produced in the bottom of the groove G. 55

As thus made, when the rounded hinging end of the latch-bolt is passed down from the top through the eye of the body, and drawn frontward so as to bring the journals h h into the bearings b b of the body, with the rounded 60 part of the hinging end of the latch-bolt within the opening O at the end of the groove G, and the cross-partition c' against the inner face of the rounded end E of the latch-bolt, the spring being within the recess R, then the hook end 65 of the latch-bolt, made as indicated at Fig. 3, with an offset, is bent so as to be parallel with the body and over the closing end of the latch-bolt L, and a very simple and serviceable hinge-connection is made between the snap-body 70 and the latch-bolt thereby. The parts of the hinge thus made require no fitting, being cast on and with the parts with which combined.

In a patent granted to me as inventor, dated 75 January 22, 1884, No. 292,164, a similar hinging-connection is shown, but in which no groove was had in the latch-body, there being a central pin in the body, constructed to be within a recess between the hinging-journals, to prevent lateral motion, while in the device shown herein the hinging mechanism is dependent upon the connection made between the latch-bolt and the cut-out end of the groove O. 80

By forming the body of the snap-hook with 85 the opening or cut-out portion O, I provide a ready and convenient seat for the journals of the snap below the face of the body, and dispose of the downward-projecting part E in the cut-away part beyond displacement under 90 ordinary exigencies; and by providing the longitudinal groove G with the transverse partitions c c' and opening in the bottom of the recess, and forming the snap with the recess N and pin p, I secure a reliable seat for the actuating-spring, and provide means for the escape of small substances through the hole in the recess R, which might otherwise find lodgment 95

therein and prevent the spring from acting and the parts from operating. The construction of the means for retaining the spring in position admits of the interposition of a detachable or loose spring; and since this part of the device is the one which usually wears out or breaks, it is apparent that when the spring in my device becomes inoperative from any cause it can readily be renewed or replaced, and the whole device be thus restored.

Having thus described my invention, what I claim, and desire to secure by Letters Patent, is—

The improved harness-snap herein described, composed of the body B, formed with the longitudinal groove G, having cross-parti-

tions c' c², forming the recess R, provided with the clearing-hole d in the bottom thereof, the rear cut-away portion, O, and bearings b b, and the snap-latch L, formed with rounded end 20 E, provided with journals h h, the recess N, having the projecting pin p and the interposed spiral spring S, all combined and arranged to operate substantially as described, and for the purposes set forth.

Signed at Troy, New York, this 3d day of July, 1884, and in the presence of the two witnesses whose names are hereto written.

JOHN GIBBONS.
